GRANT HOBART LIGHT, OF LEBANON, PENNSYLVANIA.

DENTAL IMPRESSION TRAY.

Application filed August 3, 1925. Serial No. 47,970.

This invention relates to devices ordinarily known as "impression trays" useful to dentists in making with plaster of Paris or other plastic compositions, casts or impressions of the mouth, serviceable as records of dental operations finished, or to facilitate subsequent dental work such as constructing artificial teeth, plates, etc.

The main object of my invention is to enable, in connection with a dental device of the type mentioned and after the same is placed in the mouth of the patient, compression of the plastic composition to force it uniformly against the teeth and evenly upward and rearward against the alveolus and hard palate to insure a perfect and accurate inverse reproduction of all cavities, recessions and undulations, regardless of their size and configuration; and thus to provide an impression entirely devoid of air holes and other imperfections attending impression making with devices heretofore available for this purpose.

My invention is further directed toward securing the above desiderata in a dental impression device which is comparatively simple in construction and reliable in operation; inexpensive to manufacture; extremely light in weight, yet sufficiently sturdy to resist distortion under pressure of the plastic during application as aforesaid; and very easy to manipulate.

Other objects and advantages will be manifest from the description hereinafter of the typical embodiment of my invention shown in the drawings, whereof Fig. I is a plan view.

Fig. II is a side elevation of the device as viewed from the bottom of Fig. I, with certain parts broken away and in section to disclose important structural details;

Fig. III is a rear end view; and

Fig. IV is an inverted plan view of the organization.

As shown, the device comprises a bottom member 5 preferably constructed of a light non-corrosive sheet metal such as aluminum, and fashioned to semi-elliptic contour with the center raised as at 6 to simulate the shape of the human palate. Marginal portions along opposite side edges of the bottom member 5 are overlapped by inwardly-extending base flanges 7 of flanking side members 8—also constructed of aluminum

or the like—with upstanding retaining walls 9, said side members being exact reverse counterparts of one another and suitably formed to correspond in configuration to the contiguous side edges of the bottom member which they respectively overlap. As a consequence of this construction, the component members, 5, 8, jointly provide a perimetrically-closed tray to hold an adequate quantity of the plastic which is to serve as the base for the impression. As best seen in Figs. I and IV, the complementary flanking side members 8 abut centrally at the front of the bottom member 5, and are there joined by an arcuate leaf spring 10, in the present instance conveniently secured to them by rivets 11—said spring, by virtue of its position, tending to resist movement of the members 8 laterally relative to each other and the bottom member 5.

Referring more particularly to Figs. II, III and IV, it will be observed that the flanking side members 8 aforesaid are coordinated, adjacent their rear ends, with the bottom member 5 by pin and cam slot connections, each comprehensively designated 12. These connections 12 conveniently, though not essentially, comprise brackets 13 which are secured to the corresponding side members 8 by rivets 14, and bent horizontally as at 15 to underlap the side edges of the bottom member 5, thereby to assist in holding the several parts against becoming disengaged during manipulation of the tray. The underlapping portions 15 of the brackets 13 are characterized by complementarily-sloped open-ended cam slots 16 for engaging pins 17 which are anchored in, and depend from, the bottom member 5, as shown in Figs. II and IV. Accordingly, with longitudinal movement of the member 5 in one direction or the other relative to the flanking side member 8, the pin and cam slot connections 12 will effect either compensative lateral separation or approach of said side members to expand or contract the tray.

For the purpose of shifting the parts 8, as just described, I employ the screw means such as shown at 18, the same including a threaded shank 19 which is conveniently secured at 20 to the front end of the bottom plate 5, and projects forwardly for engage-

ment therewith of an adjusting nut 21 that is sustained for free rotation in a bearing 22 suspended from the leaf spring connector 10.

5 In making an impression with my improved tray, the procedure is as follows:

The tray is first expanded to the full limit and filled with the plastic, it is then placed in the mouth of the patient, and a 10 "snap" impression made simply by pressing the device bodily against the palate. As a result of this snap impression, the amount of plastic over and above the quantity actually needed is forced out of the tray.

15 After removal of the displaced excess plastic, the device is replaced within the patient's mouth and firmly held against the palate with one hand, while the other hand is employed in manipulating the thumb nut 20 21 to effect contraction of the flanking side members 8, 8 relative to the bottom member 5, with the result that the plastic is compressed and forced uniformly and evenly outward against the teeth as well as against

25 the alveolus and hard palate. After allowing the proper interval for the plastic to set, the device is again withdrawn, whereupon the cast may be removed from the tray by expanding the latter through reverse manipulation of the thumb nut 21, i. e., to sufficiently separate the flanking side members 8, 8 for removal of the cast without danger or injury to the same. In this connection it is to be particularly noted that 30 the screw means 18, in addition to serving as the means to manipulate the device, functions to hold the component parts locked in whatever position placed.

As a result of being constructed almost 40 wholly of aluminum, the device is very light in weight yet amply strong and sturdy to resist rough usage as well as distortion when manipulated to compress the plastic material incidentally to making an impression. Furthermore, the structural simplicity of my improved dental tray renders its manipulation extremely easy and quick, insures reliability in continued use, and facilitates its manufacture at very small cost.

45 Having thus described my invention, I claim:

50 1. A dental device for making impressions of plastic material comprising component parts interconnected for relative movement, and a common actuator adapted to simultaneously shift the parts to effect both longitudinal and lateral contraction of the device after placement in a patient's mouth.

55 2. A dental device for making impressions of plastic material comprising expansile component sections jointly forming a perimetricaly closed tray for the plastic, and means enabling relative contraction of said component sections laterally and longitudinally, after placement of the device in

the patient's mouth, to compress the plastic and force it outward against the alveolus and hard palate.

3. A dental device for making impressions of plastic material comprising expansile component sections interengaged by pin and cam slot connections; and means to enable shifting of said component sections laterally and longitudinally, after placement of the device in the patient's mouth, to compress the plastic and force it uniformly outward against the alveolus and hard palate.

4. A dental device for making impressions of plastic material comprising a bottom member; relatively-expansile flanking side members; and means to shift said members laterally and longitudinally with respect to the bottom member, after placement of the device in the mouth of the patient, to compress the plastic and force it outwardly against the alveolus and hard palate.

5. A dental device for making impressions of plastic material comprising a bottom member; relatively-expansile flanking side members movable about a point centrally of the front of the bottom member; and means to enable simultaneous contraction of said members laterally and longitudinally with respect to said member, after placement of the device in the patient's mouth, to compress the plastic and force it outwardly against the alveolus and the hard palate.

6. A dental device for making impressions of plastic material comprising a bottom member; flanking expansile side members engaged by pin and cam slot connections with said bottom member; and means for shifting the bottom and side members longitudinally and laterally after placement in the mouth of the patient, to actuate said pin and slot connections in contracting the device to compress the plastic and force it outwardly against the alveolus and hard palate.

7. A dental device for making impressions of plastic material comprising a bottom member; flanking expansile side members engaged by pin and cam slot connections with said bottom member; and screw means enabling shifting of the bottom and side members longitudinally and laterally, after placement in the patient's mouth, to actuate said pin and cam slot means in contracting the device to compress the plastic and force it outwardly against the alveolus and hard palate.

8. A dental device for making impressions of plastic material comprising a bottom member; relatively-movable flanking side members abutting centrally of the front of the bottom member and there connected to each other by a leaf spring; and means to enable simultaneous contraction of said

side members laterally and longitudinally relative to the bottom member, after placement in the patient's mouth, to compress the plastic and force it against the alveolus and hard palate.

9. A dental device for making impressions of plastic material comprising a bottom member; flanking side members abutting centrally of the front of the bottom member and there connected to each other by a leaf spring; pin and cam slot connections between the rear ends of the flanking side members and bottom member; and means to enable shifting of the several component members longitudinally and laterally, after placement in the patient's mouth, to actuate said pin and slot connections in contracting the device to compress the plastic and force it outwardly against the alveolus and hard palate.

10. A dental device for making impressions of plastic material comprising a bottom member; flanking side members abutting centrally of the front of the bottom member and there connected to each other by a leaf spring; pin and cam slot connections joining the rear ends of the flanking side members with the bottom member; and screw means to enable shifting of the bot-

tom and side members longitudinally and laterally, after placement of the device in the patient's mouth, for actuation of said pin and cam slot connections in contracting the device to compress the plastic and force it outwardly against the alveolus and hard palate, said screw means also functioning to hold the component members locked in whatever position placed.

11. A dental device for making impressions of plastic material, comprising a bottom member; expansively connected flanking side members overlapping marginal portions of the side edges of said bottom member; brackets on the side members underlapping the marginal portions aforesaid of the bottom member to assist in holding the parts in assembly; and projections on said bottom member engaging complementary inclined cam slots in the underlapping portions of the brackets aforesaid for cooperation in effecting simultaneous lateral and longitudinal shifting of said flanking side members relative to the bottom member.

In testimony whereof, I have hereunto signed my name at Lebanon, Pennsylvania, this 24th day of July, 1925.

GRANT HOBART LIGHT.
